UNITED STATES PATENT OFFICE.

FRANK FEHR, OF LOUISVILLE, KENTUCKY.

ELEVATOR-HATCHWAY SEAL.

1,406,951.

Specification of Letters Patent. Patented Feb. 14, 1922.

Application filed October 23, 1920. Serial No. 419,067.

To all whom it may concern:

Be it known that I, FRANK FEHR, a citizen of the United States, residing at Louisville, in the county of Jefferson and State of Kentucky, have invented certain new and useful Improvements in Elevator-Hatchway Seals, of which the following is a specification.

The invention relates to elevator installations in building construction.

It is frequently necessary in housing certain classes of business that the building be constructed so that rooms on different floors, or whole floors, may be sealed from the remainder of the building and from the outside atmosphere. At the same time it is necessary to provide communication with elevator service for the movement of goods or the passage of persons. It may be desirable to segregate portions of a building so that noxious odors, dust, or other undesirable by-products incident to industrial processes can be confined therein. The even maintenance of high temperatures in drying rooms wherein materials are being constantly moved to and from an elevator is frequently required.

In cold-storage warehouses the maintenance of uniform temperatures is particularly essential to the preservation of perishable goods, and to that end the rooms and floors are provided with communicating doors which effect an air seal when closed.

In using an elevator for the movement of goods in and out of a cold storage warehouse and between floors, it is of course necessary to open the hatchway doors. In the usual construction of elevator installations, the shaft acts as a flue to create a circulation of air through the door openings when in use. The resultant disturbance of temperatures in refrigerated rooms not otherwise protected is obviously considerable and objectionable.

In order to avoid the escape of cold air from the refrigerated rooms through the doors when opened to allow passage into or out of an elevator it has been customary to construct cold-storage buildings with closed

vestibules at the doors leading into the elevator hatchways, the vestibule door being closed before the hatchway door is opened so as to minimize the escape of cold air. These vestibules, however, take up considerable space which but for their presence could be used for storage.

It is one of the general aims of my invention to produce an improved construction for cold-storage and other buildings which eliminates the necessity for vestibules and at the same time effectively prevents the flow of currents of air between an elevator hatchway and any room with which the elevator car is to be placed in communication.

I accomplish this object by building the elevator car with sealed walls except for the entrance-and-exit opening in the car, and by providing means for practically and positively sealing the spaces between the edges of the car opening and the shaft walls about the hatchway door, so that air cannot flow through such spaces when the elevator is in register with a hatchway door.

Another object of my invention is to provide means which is automatic in its operation and does not require the attention of the operator to effect a seal when the car is positioned before the door opening.

A further object is to provide sealing means of great durability, and of simple construction which may be cheaply manufactured and installed on standard types of elevators.

The objects of the invention thus generally stated, together with other objects and advantages which will be apparent as the description proceeds, are attained by the construction and arrangement hereinafter described and illustrated in the accompanying drawings, forming part hereof.

Fig. 1 of the drawings is a fragmentary sectional elevation of a building constructed with an elevator hatchway within a walled shaft and equipped with an elevator car and operating means therefor. The car and shaft are shown in section as taken on the vertical plane indicated by the line 1—1 in Fig. 2.

Fig. 2 is a sectional plan view of the car and shaft taken on the horizontal plane indicated by the line 2-2 in Fig. 1.

Fig. 3 illustrates in vertical cross section 5 the means employed to seal the spaces between the top and bottom of the car and the shaft wall adjacent to the door opening.

Fig. 4 is a cross sectional view of my device adapted to seal the lateral spaces between the car and wall, and also shows a fragmentary plan view of the construction 10 illustrated in Fig. 3.

Fig. 5 illustrates in cross section a modified construction of the means employed to 15 seal the lateral spaces.

Fig. 6 is a fragmentary side view of the device constructed as illustrated in Fig. 5, and showing broken sections representing the top, bottom and an intermediate portion 20 of the car.

In the embodiment of my invention selected for illustration, referring now to Figs. 1 and 2, the numeral 5 indicates the foundation of a building from which rise 25 the walls 6 and 7 forming respectively the front and rear walls of an elevator shaft enclosing one or more hatchways. The several floors of the building are indicated at 8. Opening from each floor into the elevator shaft are doors 9 formed in the wall 6. An elevator car 10 operates within the shaft, and travels upon the guide rails 11 suitably secured at the sides of its hatchway, and with which the car is engaged by means of 30 some one of the well known safety devices adapted to that purpose. A cable 12, attached to the top of the car, passes over a sheave 13 and is wound upon a revolving drum 14. Driving mechanism, including power means controlled by the elevator operator, is indicated generally at 15, and serves to actuate the drum 14 and the cable 12 by which the car 10 is raised and lowered in the shaft. A counterweight 16 (Fig. 2) 40 is arranged in a well known manner to counterbalance the weight of the car 10. The car is constructed with its side and rear walls, and also its top and floor, closed to the circulation of air, the front of the car which faces the hatchway doors 9 being open.

It will be seen that between the front of the car 10 and the wall 6 there must be operating clearance to permit the passage of the car in the hatchway. The clearance 55 allowed in practice is sufficient to permit a large volume of air to pass between the adjoining rooms of the building and the shaft when the car is positioned before one of the openings and the doors opened to handle freight from the elevator; a condition heretofore requiring the construction of space-consuming vestibules with double sets of doors.

To prevent that action I have mounted 60 flexible strips about the four sides of the

front face of the car 10 which extend forwardly to engage outstanding elements fixed to the wall 6 surrounding the door openings, and which cooperatively form an air seal about the front face of the car when 70 it is positioned before one of the openings. My preferred construction to accomplish this seal comprises rails 17 (Figs. 1 and 4), preferably being standard guide rails, fixed in vertical position upon the wall 6, one on 75 each side of and adjacent to the openings 9, and extending continuously the entire length of the hatchway. Immediately above and below each of the door openings is mounted a cross member 18 extending between the 80 side rails 17 and projecting into the hatchway. The surface of the cross member is inclined toward the wall at its upper and lower edges.

Angular supporting brackets 19 (Figs. 1 85 and 2) are suitably secured on each side of the car 10 near and parallel to the edges of its front face and extending a substantial distance above and below the car frame. The sealing devices mounted thereon on each side 90 of the car being identical in construction, only one will be described as illustrated in Fig. 4. Carried at intervals on the front face of the bracket 19 are filler blocks 20 to which are attached an angle plate 21 extending along the length of the bracket 19, and mounted with its angle projecting forwardly. Secured oppositely on the angular faces of the plate 21 is a pair of flexible strips 22 running longitudinally of the plate, 95 and with their front edges extending substantially forward of the front face of the car to engage between them the outstanding tongue of the rail 17. The strips 22 are maintained in yielding contact with the rail 100 by means of a spring member 23 overlying each of the strips 22 throughout their length and detachably secured along the rearward edges of the strips to the plate 21, as by means of cap screws 24 passing through the 105 strips. The spring members also serve as clamps to hold the flexible strips in place. The strips 22 being of considerably greater width than the faces of their support and being mounted in spaced angular relation 110 to each other, their forward edges are forced into contact with the rail 17 and resiliently held in such contact by the overlying springs. The strips are constructed of a tough durable material suitable to their continual frictional engagement with the rail. I have found that standard leather belting 115 gives satisfactory results in use as such strips.

It will thus be seen that the lateral spaces 120 between the car 10 and the wall 6 are closed against air circulation therethrough, and that the construction just described permits of the movement of the elevator through its hatchway with the flexible strips constantly 125 130

and automatically performing their function in their sliding engagement with the cooperating rails.

Across the top and the bottom of the car and in similar parallel relation to its front face I have mounted sealing devices of identical construction with that indicated by the numerals 19 to 24 inclusive, and illustrated in Fig. 3 as indicated by the numerals 19^a to 24^a inclusive, which shows the device as applied to the top of the car.

The strips 22^a meet at their outer edges and extend sufficiently forward to form a double contacting element engaging the convex surface of each of the plates 18 as the car passes them successively in its hatchway. The resilient construction of the strips permits them to yield, slidably pass over the convex plates in either direction, and return to normal position. When the car is stopped before one of the doors the strips remain in contact with the plate mounted oppositely. The strips 22^a are formed to extend substantially in complete closure between the upper and lower projections of the lateral strips 22.

For the adjustment of the relative position of the flexible strips above and below the car to compensate for wear, base plates 30 25 (Fig. 3) are fixed upon the top and the bottom of the car, and carry the supporting brackets 19^a. Transverse slots 26 are formed in each of the brackets 19^a through which securing bolts 27 are engaged with the plate 35 25. As the flexible strips wear, the support may be moved forward to effect proper contact between the strips 22^a and the cooperating convex plates 18.

In the modified construction of the side sealing device illustrated in Figs. 5 and 6, an angular supporting bracket 19^b is carried on each side of the car 10 adjacent to its front face. An angle plate 21^b, coextensive in length with the support 19^b, is secured thereto along one of its faces, by means of bolts 27^b carried by the support and passing through elongated slots 26^b in the angle plate 21^b to permit lateral adjustment of the latter relative to the car. On the opposite web of the angle plate 21^b, which extends forwardly and parallel to the side of the car, is secured a pair of flexible strips 22^b running longitudinally of the plate. The strips are mounted in spaced parallel relation, their rearward edges being separated by a spacer block 20^b and attached to the plate 21^b by means of bolts 24^b. The forward edges of the strips extend forward to embrace the tongue of the rail 17^b secured to the wall of the shaft. Contact between the strips and the rails is yieldingly maintained by a plurality of clamping elements 23^b carried by the flexible strips and spaced along their forward edge. Mounted oppositely on the outer faces of the strips, the clamping ele-

ments are positioned with their inner edges overlying the center portions of the strips whereat spacer pieces 28 are secured between the strips, and with their outer edges overlying the forward edges of the strips which 70 embrace the rail. A bolt 23^d passes through the clamping elements and strips and has its head bearing upon one of the clamping elements. A coiled spring 23^e is mounted on the extended end of the bolt and tensioned 75 between the nut 23^e and the other of the clamping elements, thus tending to yieldingly draw the latter together and thereby maintain contact between the strips and the rail in their sliding engagement.

It will now be apparent that when the car 10 is positioned on a level with either of the building floors in register with one of the door openings 9, a complete seal is effected, closing the spaces surrounding the front face 80 of the car. In that position the flexible strips above and below the car are in contact with the oppositely positioned convex members fixed about the door, and, with the constantly engaged lateral strips, accomplish the 85 prevention of any air circulation between the hatchway and the open doors. It will also be apparent that by the use of my invention the objectionable vestibules now commonly in use may be discarded. It will be 90 further obvious that the action of the sealing devices is wholly automatic and needs no attendance by an operator. The principal elements are of standard fabricated materials providing cheapness of construction, and their design assures durability in service. It is further apparent that my invention 95 may be adapted to seal floor hatches in ele- 100 vator construction.

While I have illustrated and described in 105 detail a preferred embodiment of my invention it should be clearly understood that the disclosure is merely for purposes of illustration and that many modifications and variations will naturally occur to those skilled in 110 the art. I aim in the subjoined claims to cover all such legitimate variations and modifications.

I claim as my invention:

1. In a building having a plurality of 115 floors, the combination of an elevator car operating in a hatchway having openings at said floors, and cooperative means associated with said car and said openings to prevent the circulation of air between either of said 120 openings selectively and said hatchway, said means effecting a continuous closure between the sides of said car and said hatchway and an interrupted closure between the top and bottom of said car and said "hatchway."

2. In a building having a plurality of floors, the combination of an elevator hatchway having a wall with openings framed therein at said floors, an elevator car operable in said hatchway, means for continu- 130

ously sealing the spaces between the sides of said car and said wall, and intermittently operative means for sealing the spaces between the upper and lower portions of the 5 car and the wall immediately above and below said openings, to prevent the circulation of air between the opening and said hatchway.

3. In an elevator installation the combination of a hatchway having spaced door openings therein, a car operating in the hatchway, and means for selectively sealing said door openings from communication with said hatchway when said car is registered therewith, said means including continuous vertical members mounted in said hatchway laterally of said door openings, elements carried on the sides of said car having continuous overlapping sliding engagement with said members, and sealing devices severally mounted above and below said car and door openings adapted when registered to effect a closure between said vertical members.

25 4. In an elevator installation having a hatchway, the combination of an elevator car operating in said hatchway, a series of door openings framed in one of the walls defining said hatchway, a pair of outstanding continuous rails fixed to said wall and positioned one at each side of said series of openings in parallel relation to the direction of movement of said car, pairs of cross plates having outstanding surfaces and extending between said rails, one plate fixed above and one below each of said openings, and means carried by said car to engage with said rails and cross plates and substantially seal said hatchway against atmospheric communication with either of said openings selectively.

5. In an elevator installation having a hatchway, the combination of a wall defining a side of said hatchway and having a series of vertically arranged spaced door openings framed therein, an elevator car operating in said hatchway and having its face successively in register with said openings, forwardly extending flexible strips mounted about and surrounding the face of said car, and means secured to said wall about said door openings to engage selectively said flexible strips when the face of said car is in register with one of said openings and thereby prevent the circulation of air between the opening and the hatchway.

6. The combination with an elevator car operable to selectively register with a plurality of hatchway doors, of pairs of resilient strips mounted on the car, one pair across the top and another pair across the bottom of the door of the car and extending forwardly therefrom, the strips of each pair being angularly disposed relative to each other 65 and stressed so that their forwardly extend-

ed edges meet, horizontally positioned plates fixed in relation to said hatchway doors and located one above and one below each of said doors, each pair of plates having outstanding surfaces with inclined edges arranged to engage the longitudinal edges of said strips in the operation of said car, and remain in contact therewith when said car is positioned in register with a hatchway door, and means for sealing the spaces between the 75 car and hatchway wall at the sides of said doors.

7. The combination with an elevator car operable to successively register with a plurality of hatchway doors, of a pair of pliable strips secured to each side of said car adjacent to its face and extending forwardly therefrom, said strips of each pair being disposed in spaced relation to each other and stressed so that their forwardly 80 extended edges tend to meet, and vertically extending elements fixed in relation to said hatchway doors one on each side thereof and located forwardly of said pairs of strips, each of said elements having an outstanding tongue interposed between and in sliding contact with the forward portions of the adjacent pair of said strips.

8. In a device of the class described, the combination of an elevator car operating in a hatchway having a door opening, a support mounted on said car parallel to the vertical sides of its front face, a pair of spaced pliable elements attached to said support and extending forwardly of said car, a rail fixed in said hatchway at one side of said opening and having an outstanding tongue, said tongue being interposed in sliding engagement between said elements, and a plurality of spring stressed 95 clamping members associated with said elements tending to force together the forward portions thereof and yieldingly maintain them in contact with said rail.

9. In a device of the class described, the combination of an elevator car operating in a hatchway having a door opening, a support adjustably mounted on said car parallel to the horizontal sides of its front face, a pair of spaced pliable elements attached to said support and extending forwardly of said car, a pair of spring members associated with said elements tending to force together the forward portions of said elements and yieldingly maintain them 110 in normally extended position, and a horizontally positioned plate fixed in said hatchway adjacent to said opening, said plate being shaped with an outstanding portion having a curved vertical cross section and 115 adapted to be slidably engaged by said pliable elements.

10. In an elevator installation having a hatchway, the combination of an elevator car operating in said hatchway, a series of 120

door openings framed in one of the walls defining said hatchway, a pair of outstanding continuous rails fixed to said wall and positioned one at each side of said series of openings and parallel with the direction of movement of said car, means carried by said car and engaging with said rails to seal the spaces between the sides of said car and said wall, and means for sealing the spaces between said car and said wall at the top and bottom of said doors.

In testimony whereof, I have hereunto set my hand.

FRANK FEHR.
